UNITED STATES PATENT OFFICE.

JAMES H. PARKES, OF NASHVILLE, TENNESSEE, ASSIGNOR TO FOSTER, WELL & PARKES, OF NASHVILLE, TENNESSEE, A FIRM.

TEMPORARY BINDER.

No. 856,800.

Specification of Letters Patent.

Patented June 11, 1907.

Application filed February 7, 1907. Serial No. 356,246.

To all whom it may concern:

Be it known that I, JAMES H. PARKES, a citizen of the United States, residing at Nashville, in the county of Davidson and State of Tennessee, have invented certain new and useful Improvements in Temporary Binders, of which the following is a specification.

My invention relates to improvements in temporary binders, of what is commonly known as the "loose leaf ledger" type, and the object of my invention is the provision of a ledger consisting of a series of independently bound sections of leaves so that the size of the book may be increased or reduced by adding thereto or removing as many of the sections as necessary, and also to bind the leaves in each section, removably, so that the number of leaves in each section may be varied to suit different conditions and requirements.

Another object of my invention is the provision of means for binding loose leaves in book form so that the book may be opened out wide with the leaves spread flat, without injury to the leaves or the binding, and a further object is to provide a simple construction of loose leaf ledger in accordance with the above named objects, which will be thoroughly practical and efficient for all purposes.

With these and other objects in view, my invention consists of clamping members for removably binding a number of loose leaves, said members being interchangeable and removably secured to each other so that the number of sections of leaves may be varied by joining any number of the clamping members together, and covers secured to the outer clamping members to afford protection to the leaves.

The invention further consists of a loose leaf ledger embodying certain other novel features of construction, combination and arrangement of parts substantially as herein disclosed, and as shown in the accompanying drawings, in which:

Figure 1, is a plan view of my improved loose leaf ledger looking downward upon the same, the book being opened at the center. Fig. 2, is an edge view of the same. Fig. 3, is another edge view, parts being shown in section to illustrate the manner in which the different binding sections are pivotally secured together. Fig. 4, is an enlarged detail view of two adjacent binding sections, the

parts being open to receive the leaves therebetween. Fig. 5, is a sectional view of the same taken on line 5—5 of Fig. 4. Fig. 6, is a cross sectional view of the assembled book or loose leaf ledger. Fig. 7, is a broken detail view of one of the back plates to one of the binding sections, with the securing clip hinged to the end thereof. Fig. 8, is a broken cross sectional view of one of the ends of a binding section to show the application of the binding clip thereto.

The covers 1, to the ledger or temporary binder may be made of board or any other similar material having sufficient stiffness, and secured to the inner upper edges of the covers by means of screws or other suitable fastenings 2, are the hinge plates 3, provided along their inner edge (and preferably formed integral therewith) with the spaced sleeves 4, to form one portion of a hinge joint. As before stated, the leaves are bound in sections, each clamping section comprising a back plate or strip 5, having spaced hinge sleeves 6 formed on the longitudinal edges thereof, and the pair of side plates or clamping strips 7, having similar hinge sleeves 8, formed on their edges to alternate with the sleeves on the back plate. The sleeves on the hinge plates 3, carried by the covers, the clamping strips 7, and the back plate 5, alternate in respective order and pintles 9, are passed through the alining sleeves in order to form a hinge joint between the cover hinge plate, the back plate and the clamping strip, so that the three said members are pivotally secured together. The back plates of the adjacent sections and the clamping plates carried thereby, are also pivotally secured together by means of a common pintle 10, which passes through the alining sleeves of the members, the sleeves of the different members being arranged to alternate in proper order.

In each clamping section, one of the side plates is provided with a pair of conical studs 11, located near the ends thereof and on the inner face of the plate, which studs coöperate with and are adapted to enter and engage the tubular posts 12, secured in corresponding positions upon the face of the opposite side plate. The leaves of the book are formed with the proper sized openings on their binding edge to pass over the tubular posts, and after the leaves are in place on the

tubular posts, the opposite strip carrying the pointed studs is hinged over in engagement with the tubular post as illustrated in Fig. 6. The coöperating tubular posts and conical studs thus form paper guides for retaining the sheets in proper position. In order to securely hold the clamping plates or side strips in this closed position and prevent displacement of the leaves from between the side strips, binding clips 13, are hinged to the ends of the back plates, these clips having laterally directed clamping portions 14, to engage the outer face of the side strips and clamp the strips together, in the manner shown in Fig. 8. In order to prevent accidental release of the binding clips, one of the laterally directed portions or fingers of each clip is preferably formed with a raised head or protuberance 15 on its inner face adapted to ride over the edge of the corresponding side plate and engage the recess 16, formed in the face thereof, which feature is also illustrated in Fig. 8.

From the foregoing, it will be seen that the adjacent binding sections and the covers are all pivotally secured together so that the book may be opened flat to any page without causing a strain or wear upon any of the parts thereof. Each binding section forms a distinct part so that if desired, different accounts may be kept in the different sections with accuracy and perfect ease. If desired to add more sections to the book, the pintle connecting the adjacent sections may be removed, and one or more sections inserted as desired, so that the size of the book may be governed to suit different requirements. The number of the leaves in each section may be altered by opening the clips at the ends of the section and either adding to or removing any number of the leaves. In order to protect the outer leaves in each section, cover leaves 17, of heavier material are preferably added, as shown in Fig. 3.

From the above description taken in connection, the general usefulness and many advantages of my improved ledger will be readily appreciated, and it will be apparent that I have accomplished all the results herein set forth as the objects of the invention.

I claim:

1. A loose leaf ledger comprising separable binding sections each consisting of a back plate and pivoted side plates adapted to clamp leaves therebetween, clips for securing the side plates together, covers hinged to the outer sections, the sections being connected by removable pintles so that more sections may be inserted between the outer sections said pintles being common to the adjacent sections for securing the back plates and side plates.

2. A loose leaf ledger comprising independent binding sections, each consisting of

a back plate and two side plates, pintles for pivoting the side plates to the back plates, end clips pivoted to the back plates to clamp against the side plates, and coöperating paper guides carried by the opposing side plates. 70

3. A loose leaf ledger comprising independent binding sections each consisting of a back plate and two side plates, pintles pivotally securing the side plates to the back plate, end clips pivoted to the back plates to clamp 75 against the side plates, coöperating paper guides carried by the opposing side plates, and covers to the ledger, the pintles forming the common pivotal joint between the adjacent binding sections and the covers. 80

4. A loose leaf ledger comprising independent binding sections each consisting of a back plate and two side plates, pintles pivotally securing the side plates to the back plate, end clips pivoted to the back plates to clamp 85 against the side plates, studs carried by one of the side plates, and tubular guides carried by the opposing side plate to receive said studs.

5. A loose leaf ledger comprising independent binding sections each consisting of a back plate and two side plates, pintles pivoting the side plates to the back plate, end clips pivoted to the back plates to clamp the side plates together, studs carried by one of the side plates of each section, tubular guides 95 carried by the opposing side plate to receive the studs, covers pivoted to the outer binding sections, the pintles extending full length of the sections and forming the common joint between the side and back plates and the 100 covers.

6. A paper binding section comprising a back plate and side plates each formed with coöperating hinge sleeves, hinge pintles passing through said sleeves, end clips hinged to 105 the back plate having overhanging extensions to embrace the side plates, conical studs carried by one of the side plates, and tubular guides carried by the opposing side plate to receive the studs. 110

7. A temporary binder comprising independent binding sections each consisting of a back plate and side plates formed each with coöperating hinge sleeves, hinge pintles passing through said sleeves, end clips hinged to 115 the back plate having extensions to embrace the side plates, studs carried by one of the side plates, tubular guides carried by the opposing side plate to receive the studs, the pintles passing through certain of the hinge 120 sleeves on the adjoining back plates to hinge the sections together, and covers hinged to the outer sections by means of the pintles on the outermost sections.

In testimony whereof I affix my signature 125 in presence of two witnesses.

JAMES H. PARKES.
Witnesses:

L. M. MULLENS,
ORRIS E. DAVIS.

It is hereby certified that the name of the assignee in Letters Patent No. 856,800, granted June 11, 1907, upon the application of James H. Parkes, of Nashville, Tennessee, for an improvement in "Temporary Binders," was erroneously written and printed "Foster, Well & Parkes," whereas said name should have been written and printed *Foster, Webb & Parkes*; and that the said Letters Patent should be read with this correction therein that the same may conform to the record of the case in the Patent Office.

Signed and sealed this 2d day of July, A. D., 1907.

[SEAL.]

C. C. BILLINGS,

Acting Commissioner of Patents.
